UNITED STATES PATENT OFFICE.

HERMANN HOPP AND LEO HOPP, OF NEW YORK, N. Y.

TICKET HOLDER.

1,417,325.

Specification of Letters Patent. Patented May 23, 1922.

Application filed January 14, 1922. Serial No. 529,163.

To all whom it may concern:

Be it known that we, HERMANN HOPP and LEO HOPP, both citizens of the United States, and residents of the city of New York, borough of Manhattan, in the county and State of New York, have invented a new and Improved Ticket Holder, of which the following is a full, clear, and exact description.

10 The present invention relates to new and useful improvements in ticket holders, and it pertains more particularly to devices adapted for holding price tickets.

It is one of the objects of the invention 15 to provide a ticket holder which may be securely fastened to the edge of a shelf or similar structure.

It is a further object of the invention to provide a ticket holder in which the ticket 20 is securely held against accidental displacement.

It is a further object of the invention to provide a ticket holder in which the ticket is secured by resilient tongues.

25 It is a still further object of the invention to provide a ticket holder in which the entire device is formed from a single piece of material.

With the above and other objects in view, 30 reference is had to the accompanying drawings, in which—

Figure 1 is a perspective view of a ticket holder constructed in accordance with the present invention;

35 Fig. 2 is a horizontal sectional view taken on the line 2—2 of Fig. 1;

Fig. 3 is a vertical sectional view taken on the line 3—3 of Fig. 1.

Referring more particularly to the drawings, the device comprises a main body portion 5, from the opposite side edges of which project two parallel flanges 6. The device is formed from a single piece of material and is crimped along the lines indicated by 40 the reference character 7 to provide the main body portion 5 and the parallel flanges 6. Each of these parallel flanges 6 is provided with an inwardly projected bead 8, extending throughout the length thereof, and the upper flange is provided with a plurality of perforations 9 or the like, the purpose of which will be hereinafter more fully set forth.

When the device is in operative position,

the body portion 5 forms the front wall or face thereof, and said face is cut out as indicated at 10, to provide a plurality of resilient clasps or fingers 11. Each of these clasps or fingers 11 is provided with a depressed portion 12, and said depressed portion is adapted to normally lie within the openings 13 formed by the cut-out portion. These clasps or fingers extend from a point adjacent the lower line of the crimped portion 7 vertically, and their upper ends 14 are adapted to permit of the insertion of a card or the like 15 behind said resilient clasps or fingers. It will further be noted that these clasps or fingers are formed in the front wall of the U-shaped member at 16 a point inwardly of the ends of said front wall in order that the fingers may have a binding action with the defining edge of the openings 13.

In operation, the device is engaged with 75 the edge of a shelf 20 or the like, as shown in Fig. 3, the beads 8 frictionally engaging the shelf to retain the device in position.

If it is desired to immovably secure the device to the shelf, suitable fastenings are 80 passed through the openings 9.

With the device in the above described position, the card 15 is inserted behind the upper ends 14 of the clasps or fingers 11, and said card is then forced downwardly 85 into engagement with the depressed portions 12 of said clasps or resilient fingers 11. By constructing the device as described, it will be seen that the card 15 is forced inwardly of the open portions 13 from which the 90 clasps or fingers 11 are cut, thus distorting the card sufficiently to prevent its accidental displacement from behind the resilient clasps or fingers 11.

From the foregoing it is apparent that the 95 present invention provides a new and improved form of ticket holder in which tickets or cards may be securely held against accidental displacement, and, at the same time, said cards may be readily removed 100 when desired.

We claim:

As an article of manufacture, a ticket holder adapted for attachment to the edge 105 of shelves and comprising a substantially U-shaped member, the leg portions of which are adapted to receive the shelf therebetween, one of said leg portions having per-

forations provided therein for the reception of fastening means, an inwardly disposed integral bead formed on each of the leg members, a plurality of retaining clips 5 formed in the base of the U-shaped member by cutting the said base and forcing the clips therefrom, and an inwardly disposed

depressed portion formed on each of said clips, the protuberance formed on each of said depressed portions lying within the confines of the opening resulting from the formation of its respective clip. 10
